PERCUSSION DRILL BIT FOR LARGE HOLES

John Anders Hjälsten, Sandviken, Sweden, assignor to Sandvikens Jernverks Aktiebolag, Sandviken, Sweden, a corporation of Sweden

Application June 27, 1956, Serial No. 594,290

2 Claims. (Cl. 255—64)

This invention relates generally to drill bits, and more particularly to percussion drill bits for drilling large holes in rock and other hard surfaces.

An object of the invention is to provide a drill bit which will drill large holes in rock by a one-step operation when provided with a satisfactory drill feed.

Another object of the invention is to provide a drill bit which facilitates the drilling of large holes in rock by use of percussion energy without unnecessarily crushing the rock chips produced.

A more specific object of my invention is to provide a drill bit adapted to chip off pieces of rock of such size that they may easily be removed from the percussion area and the drill hole.

Still another object of the invention is to provide effective means for the removal of the chipped material from the drilled hole. A further object is to provide a drill bit having means for detaching the various cutting elements to allow for interchangeability or substitution of parts whereby drilling of various sizes of holes may be accomplished and easier maintenance of the tool may be effected.

These and other features of the invention will be more apparent from a study of the following specification when considered in conjunction with the accompanying drawings, in which:

Fig. 1 shows a perspective view of a drill bit in accordance with the invention;

Fig. 2 shows an elevation sectional view of the bit along line 2—2 of Fig. 3;

Fig. 3 shows a plan view of the bit; and

Figs. 4 and 5 are elevational and plan views of one modification of the inner cutting bit body.

Referring now to Fig. 1, the body 1 of the drill bit contains projections 2 peripherally arranged about the cutting area and adapted to receive outer cutting inserts 3, formed from a suitable hard metal material, such as one or more metal carbides and a binder. By "hard metal" is here and below meant a sintered product, consisting of one or more carbides, for example WC and/or other hard materials together with one or more binding metals, as cobalt and/or other metals in the iron group of the periodical system. The cutting inserts 3 are preferably brazed to the drill bit, but other suitable securing means, such as clamping, screwing, or welding, may be utilized as desired. While the cutting inserts 3 are shown in the drawings to be circularly arranged, it is also possible to arrange the elements in other configurations, such as an elliptical arrangement for example. The direction of the cutting edges is shown to be radial, but it is apparent that the elements may be arranged obliquely or tangentially if desired.

Centrally arranged within the drill body 1 and removably secured thereto is the inner bit body 4 to which are secured by brazing or other suitable means the inner cutting inserts 5. While the number of cutting elements shown in the drawings is six, it is obvious that the number of elements may be varied as desired. Similarly the

2

orientation of the cutting edges 5 with respect to the outer cutting inserts 3 may be varied as desired.

As shown in Figs. 2 and 4 the inner bit body is provided with screw threads 6 adapted to cooperate with the threaded bore 7 in the main bit body 1 to rigidly secure the inner bit body therein.

The inner cutting inserts 5 are usually in the same plane as the outer cutting inserts 3, although the inner edges may be positioned in front of the plane of the outer cutting edges to reduce wear of the outer cutting inserts. For special working conditions the bit may be manufactured so that the plane of the inner edges will be positioned behind the plane of the outer cutting edges.

As shown in Fig. 1, the inner cutting inserts 5 are spaced from the outer cutting inserts 3 by the flat surface 8 of the drill bit body. The minimum distance between the inner and outer cutting inserts according to my invention substantially corresponds with the cutting edge length of each of the outer cutting inserts 3. As a result of this construction, and in combination with the longitudinal grooves 9 in the outer surface of the main bit body, the chipped pieces of rock or stone may pass outwardly from the central portion of the cutting area and subsequently may be removed from the drilled hole. In order to aid in this removal of crushed rock from the drilled hole, a flushing medium may be applied under pressure through the bit to the cutting area through passages 10 in the bit body 1 or through passage 11 in the inner bit body 4. Thus it may be seen that the chipped pieces of rock will not be caught between the inner and outer cutting inserts and will readily be washed from the drilled bore.

It should be mentioned that the grooves 9 extend between the outer cutting inserts 3 from the surface 8 longitudinally of the drill bit body, although it is of course possible to form the grooves into angular, spiral or curved paths.

In the embodiment as shown in Fig. 2, the outer cutting inserts 3 are supported in the projections of the main bit body by the retaining ring 12 mounted transversely to the longitudinal axis of the bit and secured thereto by suitable securing means, such as by brazing. This retaining ring 12 serves not only to support the outer cutting inserts when they are brazed to the associated projections, but also to support the projections against oblique stresses during subsequent drilling, handling and transportation of the tool.

The grooves 9 in the outer surface of the main bit body thus extend radially outwardly from recesses 9' in the support ring and are inclined somewhere between 10° and 50° with the vertical. As shown in the alternate embodiment of Fig. 4, grooves 13 may be placed in the outer surface of the inner bit 4' to further aid in the flushing operation.

The drill bit body 1 is provided with a threaded bore 14 at the lower portion thereof whereby the drill bit may be secured to the drill rod 15.

During the drilling operation, relatively large chips are produced and by means of the surface 8 in the cutting area of the drill in combination with the grooves 9, 9' and 13 in the bit, no further crushing occurs and an effective use of the percussion energy is presented. As mentioned above, the smallest space between the inner and outer cutting inserts is approximately equal to the length of each of the outer cutting inserts. The outer diameter of the drill bit 1 is chosen for the drilling of larger holes, for example somewhere between 80 and 150 mm., but larger or smaller diameter holes may be produced as desired. The distance between the inner and outer cutting inserts is on the order of 12 to 20 mm., or in especial cases more.

While in accordance with the provisions of the statutes,

I have illustrated and described the best form of embodiment of my invention known to me, it will be apparent to those skilled in the art that changes may be made in the form of the apparatus described without departing from the spirit of my invention as set forth in the appended claims.

I claim:

1. A percussion drill bit for drilling large holes in rock or similar substances comprising a cylindrical main bit body having a cutting end and a drill rod securing end, said main bit body having a flat end surface at the cutting end thereof and a plurality of equally-spaced peripherally-arranged projections axially projecting from said flat end surface, each of said projections having an outer cutting bit mounted therein, a cutting insert retaining ring secured to said flat end surface of the main bit body in contiguous engagement with a portion of the innermost surfaces of said outer cutting inserts, said main bit body having a central longitudinal bore extending therethrough, an inner bit body screw-threadably mounted within said bore and having a tubular end portion axially projecting from said flat end surface, a plurality of equally-spaced inner cutting bits axially projecting from the extremity of said inner bit body tubular end portion, said outer cutting inserts being concentrically arranged with respect to said inner cutting inserts, said inner and outer cutting inserts each having cutting edges substantially normal to the axis of said main bit body, the minimum radial distance between said inner and outer cutting inserts being substantially equal to the maximum

5

length of the cutting edge of said outer inserts, said main bit body having longitudinal grooves on the outer periphery thereof extending between said main body axial projections and said insert retaining ring having recesses in the upper surface thereof in alignment with said longitudinal grooves, said inner bit body having a fluid conductive passage extending longitudinally therethrough and said main bit body having a fluid passage therein which terminates at one end in an opening in the main body flat end surface intermediate said main body projections and said inner bit body and at the other end in communication with said main body longitudinal bore intermediate the drill rod securing end and the inner bit body, whereby particles of drilled material may be readily removed from the annular space intermediate said inner and outer cutting inserts by the introduction of pressure fluid into the main body longitudinal bore from the drill securing end of the main bit body.

2. A percussion drill bit as defined in claim 1 wherein the minimum radial distance between the inner and outer cutting inserts is greater than 12 millimeters.
